UNITED STATES PATENT OFFICE

2,470,798

INTERMITTENT FLUSH VALVE

William S. White, Denver, Colo.

Application April 3, 1943, Serial No. 481,666

1 Claim. (Cl. 137—145)

1

This invention relates to flush valves, and more particularly relates to that class of valves designed for automatic intermittent operation.

The present disclosure is related to the disclosure in my co-pending application Serial No. 330,982, filed April 22, 1940, for Intermittent flow valve, and features disclosed but not claimed herein have been claimed in said application, now Patent No. 2,315,570.

It is an object of the present invention to provide a simple, durable and efficient flush valve that is suited for a variety of uses.

Another object of the invention is to provide a control of the discharge action of flush valves of the above described character to eliminate the occurrence of water-hammer in the pipelines with which it is connected.

A further object of the invention is to provide a manner in which the volume of discharge of such a valve may be changed.

Other objects reside in novel details of construction and novel combinations and arrangements of parts, all of which will be described fully in the course of the following description.

Typical embodiments of the invention have been illustrated in the accompanying drawings, and in the drawings in the several views of which like parts have been designated similarly.

Figure 1 is a vertical central section through a valve embodying features of the present invention and illustrating the position of component parts at an early stage of the filling operation;

Figure 2 is another vertical central section of the valve illustrated in Figure 1 showing the position of parts during the flushing action;

Figure 2a is a fragmentary detail vertical section illustrating the upper and lower notched seats in the parts surrounding top and bottom passages 31 and 32, respectively, which are adapted to be closed by ball valve 30;

Figure 2b is a top plan view of the structure shown in Figure 2a;

Figure 3 is a vertical central section through another valve embodying features of the present invention, and illustrating the arrangement of parts at an early stage in the filling operation;

Figure 4 is a vertical central section of the valve shown in Figure 3 showing the arrangement of parts during the flushing action;

Figure 5 is a diagrammatic view illustrating one type of installation in which the valves of the present invention are used; and

Figure 6 is an enlarged partial cross-section taken along line 6—6 of Figure 3.

Referring first to the form of the invention

illustrated in Figures 1 and 2, the valve comprises a casing C having an inlet 7 intermediate its ends and a discharge outlet 8 at one end. The end of the casing opposite outlet 8 is closed by a suitable cap member 9 preferably having a resilient gasket 10 engaging the end of casing C. This cap member has a central recess 12, the function of which will be described subsequently.

Preferably, the interior of the casing C is formed into portions of different diameter. The portion extending between inlet 7 and the end of the casing closed by cap member 9 constitutes a cylinder 13 of greatest diameter, while the interior of casing C between inlet 7 and outlet 8 is formed into a second cylinder 14 of lesser diameter than cylinder 13, and which terminates at a distance from outlet 8, in a bore 15 of lesser diameter than cylinder 14, but of greater diameter than outlet 8. Two diametrically opposed openings 16 are provided in the walls of bore 15, the function of which will be explained hereinafter.

A piston member, or primary piston P, preferably double-headed, is mounted for reciprocating movement in cylinder 13 and divides same into a receiving chamber 18 and a pressure chamber 19. In this form of the invention, the piston includes an upper head formed by a disk 20, and a two part flexible cup washer 21, 21a clampingly held on a threaded stud 22 by a nut member 23. A tubular body member 24 having a series of radially disposed passages 25 depends from the head portion or upper head and terminates in a second head portion or lower head formed by a second two part flexible cup washer 26, 26a supported by a ring member 27 held on body member 24 by a nut 28.

The primary piston P is adapted to be moved upwardly and downwardly by the difference in force created by liquid pressure exerted against the upper head and the lower head, but when pressure is exerted in chamber 19 sufficient to create a force which will overcome the above differential force, the piston will be moved downwardly. The disk 20 has a close fit with cylinder 13 and the cup washer 21, 21a provides a leak-proof packing for the upper head of the piston, although permitting movement of said head without undue frictional resistance, while ring 27 and its associated cup washer 26, 26a have a close fit with cylinder 14 and provide a leak-proof packing, while permitting movement of the lower head without undue resistance.

To provide a check valve for restraining flow to and from chamber 19, a hollow nut 29 is sup-

ported on the top of stud 22 and has a ball 30 adapted for movement in opposite directions to close a top passage 31 or a bottom passage 32 in said nut. The ball 30 is adapted to engage a lower or upper seat at the entrance to passage 31 or 32, respectively, and these seats may be notched, as shown, to control the rate of flow into and out of chamber 19. As the primary piston P moves upwardly, nut 29 is received by recess 12 in cap 9, as in Fig. 1, the recess 12 thus permitting casing C to be shorter and cap 9 to be lighter. A hollow stem 33 is supported in depending relation in stud 22 and has its lower end flanged to provide a restriction in the path of liquid flowing down outside stem 33 and also to provide a seat for a threaded collar member 34, at the upper end of a secondary piston S, which is reciprocable within and sometimes lifted by the primary piston P. Collar 34 carries a flexible washer or other packing 35, which provides a leak-proof seal with the interior wall of body member 24. A cylindrical plug 36 is inserted in the hollow interior of stem 33 and held to limited movement therein by a head portion 37 having a series of cross grooves on its upper surface, which permit a flow of liquid to chamber 19 in case head portion 37 abuts against the underside of nut 29 and tends to close off passage 32.

A threaded conduit member 38 having an enlarged head 39, extends out of the lower end of stem 33 as a lengthwise extension thereof, and has limited oscillatory movement relative to the end of said stem. Conduit 38 is adapted to convey water to and from its lower end and pressure chamber 19, via tube 33, while the head 39 of conduit 38 may be closed by plug 36, at certain times. The limit of oscillatory movement of conduit 38 is provided by a collar 40 which is fixed on conduit 38 in spaced relation to head 39, and also provides a valve between the primary and secondary pistons, as described later.

The secondary piston S also includes a hollow tube 41 threadedly attached to collar member 34 and extending in encompassing relation to conduit 38. The lower end of the tubular body 41 has an internal annular stop member 51, which acts as a seat for collar 40 at certain times. Tube 41 also is exteriorly flanged as indicated at 42, providing a seat for a two part cup washer 43, 43a which is held in place thereon by a hollow stem 44 having at its end an external thread on which an outlet valve ball 45 is mounted. The upper end of the secondary piston slides upwardly and downwardly within the primary piston, with the packing 35 in sealing engagement with the inner surface of body member 24, while the washer 43, 43a forms a lower head of larger diameter in sealing engagement with reciprocable cup R. The secondary piston may be moved downwardly by liquid pressure against the upper end thereof, when there is little or no pressure beneath the lower head, but will be moved upwardly by pressure within the cup R sufficient to create a force which will overcome the force acting on the top of the piston. The secondary piston also is adapted to be lifted upwardly by the primary piston, as in Fig. 2, when the flange at the lower end of tube 33 engages collar member 34.

Reciprocable cup R includes a tube 46 loosely supported in recess 15 and held for limited movement therein by means of a pin 47 extending through openings 16 in casing C and registering openings 47a in the tube 46. This tube supports an open-ended cylinder 48 at its upper end and the flanged end 42 of body 41 and the associated

washer 43, 43a function as a piston head in said cylinder. An extension 49 at the end of cylinder 48 provides a seat for ball 45 and the movement of cylinder 48 and tube 46 to its lower position as shown in Figure 2, will effect a valve-opening movement, the details of which will be described hereinafter.

The stem 44 has adjacent its lower end one or a plurality of openings 50 permitting filling of the interior of cylinder 48 with liquid descending through stem 33 or tube 41, so long as ball 45 remains on its seat on member 49.

In operation, the inlet 7 will be connected with a suitable source of liquid supply, and the outlet 3 will be connected directly or through the medium of a suitable conduit, with a receptacle, such as a urinal fixture, for example. Assuming the parts to be in the relative positions of Fig. 1, water entering through inlet 7 passes through receiving chamber 18 and passages 25 into the interior of tubular body member 24. From there, the water passes between the exterior of stem 33 and the interior of collar 34, and thence into the interior of tube 41, flowing past the flange at the lower end of stem 33. It will be understood that the receiving cup R is full and the water therein holds the secondary piston S in its upper position, so that the incoming water passes from the interior of tube 41 to the pressure chamber 19, either through or around stem 38, then past plug 36 and past valve 30. The flow past valve 30 takes place at a desired rate, depending on the size and number of notches in upper seat 31.

As soon as the pressure in chamber 19 is sufficient to overcome the pressure in chamber 18 (which is also exerted against the lower end of the primary piston) the primary piston begins to move downwardly. The downward movement of the primary piston P takes place relatively slowly, due to the regulated flow around ball 30 through the slots or notches in seat 31. During such downward movement of the primary piston, the secondary piston S and cup R maintain their relative positions, due to the pressure within the cup exerted against the secondary piston, and valve 45 remains closed. Also, water continues to flow into the pressure chamber 19 in the above manner, until the primary piston P descends sufficiently so that the lower end of stem 33 pushes collar 40 against stop member 51, which closes the passage around conduit 38, between the interior of tube 41 and stem 44. The primary and secondary pistons, and conduit 38 are then in the relative positions of Fig. 2, ball valve 45 being seated, however.

Water then continues to flow for a slight period to the pressure chamber 19, as through the slot 40a in collar 40, and the secondary piston S begins to be pushed downwardly by the primary piston P. This causes ball valve 45 to unseat slightly, as to the full position of Fig. 2. Also, the cup R may move downwardly until the upper edge of slot 47a strikes pin 47. The water in cup R begins to drain to the outlet, while the water in stem 44 begins to drain through the opening 50. This release of pressure within cup R causes the secondary piston to descend, valve 45 moving to the dotted position of Fig. 2. At this time, opening 50 clears extension 49, so that stem 44 will drain more directly to the outlet.

When the discharge begins, the ball 30 is reversed in position, due to flow from pressure chamber 19, instead of to the pressure chamber, as during the downward movement of the primary piston P. Due to the reduction in pressure

in chamber 19, the primary piston then begins to move upwardly from the position of Fig. 2. During discharge, not only does water flow from the pressure chamber 19, but also around stem 33 from receiving chamber 18, and then around conduit 38 and into the interior of stem 33, to join the water discharging from chamber 19. As the primary piston moves upwardly, the flange at the lower end of tube 33 catches head 39 of conduit 38, and lifts the conduit 38, so that collar 40 unseats from its seat 51, and water also flows from chamber 18, between stem 33 and collar 34, thence around collar 40 and through stem 44 to the outlet. As soon as the primary piston P begins to lift the secondary piston S, due to the flange at the lower end of stem 33 engaging the lower end of collar 34 of the secondary piston, the secondary piston S and cup R are pulled upwardly until the lower end of slot 41a in cup R engages pin 41. Further upward movement of the secondary piston S will close the ball valve, such movement being assisted by the flow of water through hole 50 into the cup R. The various parts are then in the position of Fig. 1, the pressure in cup R maintaining the secondary piston S in its upper position, as primary piston P begins to descend on the next cycle.

As will be evident, the ball valve 45 remains closed during substantially all of the downward movement of primary piston P, but remains open so that discharge takes place during upward movement of primary piston P. If desired, the collar 40 may be constructed so as to extend outwardly to the inner edge of tube 41, to guide conduit 38 during its upward and downward movement. The rate of movement of primary piston P may be regulated by varying the clearance between the flange at the lower end of stem 33 and the interior of tube 41. Also, upward and downward movement of primary piston P may be regulated by varying the number and/or size of slots in the upper and lower seats for ball 30.

It will be understood, of course, that the discharge of water from cylinder 48, after a slight opening of the valve, takes place relatively slowly, so that any tendency toward water hammer that might ensue from too abrupt release of liquid is avoided. Also, it will be observed that the closure of seat 51 by collar 40, and also the closure of the upper end of stem 33 by plug 36, prevent the escape of liquid from chamber 19 until the primary piston has fully descended, and a further release of water from cylinder 48 permits the secondary piston to be moved downwardly and seat 51 to draw away from collar 40, thus assuring a positive beginning of the next operation in the cycle. It will be further observed that reciprocal movement of cup R, while the valve ball 45 is in closed position, provides additional time between discharges.

In the arrangement just described I prefer to use the double cup washer arrangement illustrated in Figures 1 and 2. However, it will be understood that each of said cup washers 21, 21a and 26, 26a and 43, 43a are provided solely for the purpose of functioning as a leak-proof packing, and any other form of leak-proof packing capable of functioning without impeding the operative movement of the parts may be substituted in place of the double cup washers illustrated in Figures 1 and 2.

Similarly, the parts serving as pistons and the parts serving as conduits may be changed in form and dimension as required, so long as the func-

tion of such parts is not impaired. However, I have found the present arrangement of parts to be a highly satisfactory way of attaining the desired delayed discharge action previously described. An increase in the rate of flow causes chamber 19 to fill more rapidly and discharge to take place over a shorter period of time, while a decrease in the rate of flow has the opposite effect.

The form of the invention exemplified in Figures 3, 4 and 6 involves a different mode of operation in that a quick opening discharge is desired in order to suddenly release a large volume of water maintained under considerable pressure. However, with this exception, the filling and release actions in this form are a substantial duplicate of that just described.

In this form of the invention the casing C is closed at its wider end by a cap extension 61 and intermediate its ends has an inlet nipple 62 with a discharge outlet 64 near its end remote from cap extension 61. In addition, an end opening or passage 63 is provided to connect the interior of the casing with an accumulator tank 65 in a manner hereinafter to be described. This type of valve functions effectively regardless of which end is in the up position, but usually will have the passage 63 directed upwardly although the opposite arrangement has been illustrated in the drawings. When the passage 63 is upwardly directed, it usually will be preferable to have a drain cock 66 mounted at the end of extension member 61 so that the entire system may be drained as will be more fully explained herein-after.

The interior of casing C adjacent inlet 62 is divided into one cylindrical portion 67 of larger diameter and a second cylindrical portion 68 of lesser diameter. The portion of the casing interior between cylinder 68 and passage 63 is of somewhat irregular contour but substantially the same diameter as cylinder 68.

A primary piston P' is mounted for reciprocation in cylinder 67 and preferably includes a large head which comprises a threaded stud member 70 carrying a cup washer 71 and backing plate 72 in close fitting relation to the walls of cylinder 67. A hollow valve housing 73 is mounted coaxially with stud member 70 and is disposed between piston P' and the end of extension member 61. The details of the construction and function of the valve housing will be explained subsequently.

On the opposite side of the large head of the piston a tubular body 74 is carried on stud 70 and has a series of radially disposed openings 75 adjacent the stud. Tube 74 carries at its lower end a smaller head of piston P' comprising a stud 74a provided with cup washers adapted to engage the inner wall of casing section or cylinder 68 and also sealing means for secondary piston S' which slides within stud 74a. Tube 74 encases a hollow stem 76 threadedly connected with stud 70 and forming with housing 73 and stud 70 a continuous central passage. The end of stem 76 remote from stud 70 is flanged as indicated at 77 and flattened on two sides with aligned openings 78 extending through the flattened portions to communicate with the hollow interior. The end of the stem is closed as indicated at 79 to form an abutment member.

The secondary piston S' includes a threaded collar 80 mounted for sliding movement along stem 76 and in threaded connection with a sleeve

81, which in turn connects with a hollow conduit member 82 which extends through casing C' and out of passage 63.

A valve 83 normally closing the end of passage 83 is mounted adjacent the end of conduit 82 and is movable in a manner hereinafter to be described, to a position remote from the end of passage 63 to admit liquid through the passage and out of the valve through discharge opening 64.

This form of valve employs a quick opening action and for that reason is well suited for use as the control valve of a lawn sprinkling system. Such an arrangement has been illustrated in Figure 5. Preferably, the valve V is mounted in the service room 84 of a residence or other building, and is connected through inlet nipple 62 with the water supply of said building. The passage 83 connects with a pressure storage tank 65 of substantial size and the discharge opening or outlet 64 connects with a distributing system represented by the dotted lines 85, having a plurality of discharge nozzles or jets 86 disposed to sprinkle a lawn, shrubbery or the like illustrated by the dia-grammatic representation 87.

At the beginning of a given operating cycle water from inlet 62 passes into cylinder 67 and moves the piston P' to the position shown in Figure 3. This movement of the piston draws the valve 83 tight against its seat preventing any movement of liquid in and out of passage 63, particularly to outlet 64. Water entering cylinder 67 passes through openings 75 and travels between stem 76 and collar 88 which has a slight clearance therewith for regulatory purposes. The water also passes around flange 77, which may be provided with notches or slots to more readily conduct the water, and thus reaches the open end of conduit 82. Liquid continues to pass through conduit 82 into storage tank 65 for a considerable interval and as the filling progresses the body of air trapped in tank 65 is compressed to a progressively greater degree until the pressure in tank 65 balances the pressure at inlet 62. The pressure in tank 65 also holds valve 83 against its seat, since there is little or no pressure in outlet 64. To balance the pressure at inlet 62, the pressure in tank 65 need not be as great as the inlet pressure, since the pressure on the opposite side of the large head of the piston need not be as great as the inlet or receiving chamber pressure to produce a force which will overcome the differential force produced against the primary piston in the receiving chamber. Thus, an equilibrium is reached before the pressure in the tank becomes as great as the inlet pressure.

When this equilibrium is reached, the primary piston begins to move downwardly slowly until abutment 79 closes the end of conduit 82. At this time, water no longer able to travel through conduit 82 passes instead through openings 78 and the hollow interior of stem 76 until it reaches valve housing 73. A plurality of passages indicated by the dotted line representations 88, extend from the end of housing 73 adjacent stud 78 to its opposite capped end and there connect with a passageway 89 to reach a central hollow portion 90 of housing 73. A ball valve 91 controls the flow through hollow portion 90, which connects with two laterally extending ports 92, the relatively slow flow to the space on the cap side of the primary piston taking place through bleed openings or slots, around the seat, as shown in dotted lines in Figs. 3 and 4.

The force of the entering stream of water is sufficient to completely unseat the ball 91 even

when the valve casing 60 is in the reverse position from that illustrated and consequently the water discharging from ports 92 acts on piston P' to drive the same relatively rapidly away from exten-
5 sion 61. This movement opens valve 83 slightly, and the flow around valve 83 to the outlet reduces the pressure on the reservoir side of the valve. Such action takes place with sufficient velocity to force a rapid further movement of piston P' toward the end of cylinder 68, thereby unseating valve 83 and maintaining it at a considerable distance from the end of passage 63, as will be best understood by reference to Figure 4.

The accumulated contents of tank 65 are there-
10 upon forcibly discharged through the action of the compressed gas cushion therein and travel out of discharge opening 64 and through distributing system 85. The resulting release of pressure on the contents of cylinder 67, which are holding piston 69 against cylinder 68, permits a retracting movement of the piston which commences under the force of the water entering through inlet 62. However, the escape of the contents of cylinder 67 requires the liquid to flow past ball valve 91
15 through the bleed openings or slots around its seat and consequently this action delays the return movement of the piston to the position shown in Figure 3 for a substantial interval, affording ample opportunity for the liquid content of tank 65 to discharge through outlet 64 before the piston movement has progressed to a degree sufficient to again seat valve 83.

What I claim and desire to secure by Letters Patent is:

An intermittent flush valve comprising a casing having a portion of larger diameter and an inlet communicating therewith, and a portion of smaller diameter and an outlet communicating therewith; a double-headed primary piston having one head in said portion of larger diameter and dividing said portion into a receiving chamber communicating with said inlet and a pressure chamber on the opposite side of said head, and
20 a second head in said portion of smaller diameter; a tube connecting said heads of larger and smaller diameter and provided with openings for admitting liquid from said receiving chamber to the interior thereof; a stem extending centrally from the head of larger diameter within said tube and provided with inwardly and outwardly ex-
25 tending flanges at the lower end thereof; a ball valve and seats provided with flow regulating notches disposed in a bore extending through said
30 head of larger diameter and communicating with said stem; a tubular member having a head disposed within said stem and adapted to be lifted
35 by said inwardly extending flange; a collar attached to said tubular member and adapted to be moved into sealing engagement with a seat there-
40 for; a reciprocable cup having a predetermined limited motion and having a valve seat adjacent said outlet; a secondary piston extending into sealing engagement with said cup at one end and
45 at the other end into sealing engagement with the inner wall of said tube, and provided with a seat for said collar and means cooperating with said outwardly extending flange, whereby said primary piston is adapted to lift said secondary piston; a valve attached to the end of a tubular member extending from said secondary piston and adapted to co-
50 operate with the valve seat on said cup, for controlling the flow of water to said outlet, said tubular member extending through said cup and being provided with an aperture adapted to per-

mit a greater flow to said outlet from the interior of said secondary piston upon opening movement of said outlet valve, said tubular member also extending through a tubular portion of said cup and providing a clearance therewith to permit drainage of said cup upon opening of said outlet valve.
